UNITED STATES PATENT OFFICE.

HANS RIEGGER, OF BERLIN-CHARLOTTENBURG, GERMANY, ASSIGNOR TO SIEMENS & HALSKE, AKTIENGESELLSCHAFT, OF SIEMENSSTADT NEAR BERLIN, GERMANY, A CORPORATION OF GERMANY.

SUBMARINE SIGNALING APPARATUS.

Application filed May 6, 1921. Serial No. 467,355.

To all whom it may concern:

Be it known that I, HANS RIEGGER, a citizen of the German Empire, residing at Berlin-Charlottenburg, Germany, have invented 5 certain new and useful Improvements in Submarine Signaling Apparatus, of which the following is a specification.

My invention refers to submarine signaling. As is known, oscillating systems have 10 been employed as transmitters or receivers of submarine signaling apparatus, which consist of two parts acoustically coupled together. In using the term "acoustic coupling", I refer to the degree of acoustic 15 influence exerted by one oscillatory structure upon another. This influence is affected both by the natural frequencies of the coupled oscillatory bodies and by the relative proportions of the masses of these bodies. 20 One of these parts may be set into and form a portion of the outer wall of the vessel, and carries the other part consisting for instance of the diaphragm of a microphone. These devices are as a rule tuned in such a 25 way as to bring the periodicity of their natural oscillations into resonance with the periodicity of the waves to be received. For it is not intended to receive oscillations other than the desired signals. Such devices with 30 acoustically coupled elements, however, invariably possess a second additional point of resonance, which occasions disturbances.

The object of my invention is a submarine signaling apparatus, the oscillating parts of 35 which are coupled together in so loose a manner, as to obtain a one-wave system throughout, i. e. one which possesses only one single periodicity of oscillation, in which case of course both oscillating bodies must 40 be tuned practically to the same frequency. As is well known, the two-wave character of the known signaling devices is produced by the first vibrating part which receives the sound waves, and which imparts its 45 vibratory energy to the second body. After the vibratory energy of the latter has attained a certain maximum value, it reverts back to the first body. For this reason the amount of energy residing in either body decreases and increases periodically. This 50 periodic increase and decrease forms the second undesirable natural-frequency. In

contradistinction thereto the loose coupling between the oscillating bodies according to the invention is attained by making the 55 mass of the second oscillating part so small in comparison to the mass of the first part, as to cause the energy transmitted to the second part to be absorbed by the damping effect, before it can return to the first 60 oscillating part.

If the second oscillating part consists of a microphone, the construction of such a proportion of masses is difficult to accomplish and for this reason it is preferable to employ 65 a magnetophone in place of the microphone.

In the drawings affixed to the specification and forming part thereof a sound receiver as embodying my invention is represented 70 diagrammatically by way of example.

Referring to the drawings the diaphragm *m* receives the incoming waves. The pin *s* is fixed in the center of this diaphragm and forms a portion of the mass thereof and 75 carries the second oscillating part of smaller mass, the leaf-spring *f*, its free end being operatively disposed adjacent to the permanent magnet *g* of the magnetophone. It converts the mechanical vibrations into electrical oscillatory currents which are induced in coil *e* and are conducted further to the receiver *t*. The essential idea of this invention is that the mass of the leaf-spring *f* is made 80 so small in comparison to the mass of the diaphragm *m* that the system consisting of *m* and *f* only possesses one single natural 85 frequency.

The damping, by which the energy transmitted to spring *f* is absorbed, as stated in 90 the introduction to the specification, is due essentially to two causes. First, the air resistance which every element oscillating in air must overcome, and which is not useful and an absolute loss. Second, the useful 95 damping due to the spring end oscillating in a magnetic field. Therefrom two effects result: First, eddy currents are induced in the spring, which, however, in case the spring is made quite thin, are so small that 100 this source of damping may be neglected in practice. Second, through the spring oscillations the field of the magnet is varied so that currents are induced in coil *e*. This is

the actual useful damping, because if the design is properly made, the major portion of the oscillating energy of spring f is consumed in generating these useful currents, 5 which actuate receiver t .

I have found that a receiver according to the present invention is capable of absorbing more energy from the water than receivers known heretofore which have more than one 10 natural frequency.

I claim:

1. In a device of the character described the combination of two coupled oscillatory systems each system being tuned to the same 15 frequency and one system carrying the other, the mass of one system being so small compared with the mass of the other system, that the total coupled combination of the two systems has only one natural frequency, and means, operatively connected 20 with the system of smaller mass, for render-

ing perceptible the oscillations of the combined systems.

2. In a device of the character described the combination of a diaphragm and a leaf spring fixed at one end to said diaphragm, each of said elements being tuned to the same frequency, the mass of said spring being very small compared with the mass of said diaphragm so that the coupled system 25 formed by said combination has only one single natural frequency, a permanent magnet disposed relatively to said spring so that the free end of the latter is located within the field of said magnet, and a coil on said magnet in which currents are induced when the magnet field varies due to the oscillations of said spring end, and means for perceiving 30 said currents.

In testimony whereof I affix my signature.

HANS RIEGGER.
